US00D667558S

(12) **United States Design Patent**
Hakim

(10) **Patent No.:** **US D667,558 S**
(45) **Date of Patent:** **** Sep. 18, 2012**

(54) **DRINKING CUP CAP**(75) Inventor: **Nouri E Hakim**, Monroe, LA (US)(73) Assignee: **Luv n' care, Ltd.**, Monroe, LA (US)(**) Term: **14 Years**(21) Appl. No.: **29/385,506**(22) Filed: **Feb. 15, 2011**

FIG. 1 is a front view of the drinking cup cap of the present invention;

FIG. 2 is a right side view of the drinking cup cap, with the left side view being a mirror image thereof;

FIG. 3 is a top view thereof;

FIG. 4 is a bottom view thereof;

FIG. 5 is a back view thereof; and,

FIG. 6 is a front, right side, top perspective view thereof. The broken lines indicate elements which do not form part of the claim herein. The shading on the upper portion of the cap (as shown in the figures) indicates transparency.
